ARRANGEMENT FOR DISCONNECTING AND REMOVING SERIES CONNECTED TRANSFORMERS FROM THE CIRCUIT WITHOUT CAUSING DISTURBANCE

Application filed December 1, 1927, Serial No. 237,091, and in Germany December 3, 1926.

For disconnecting series connected transformers and removing them from the circuit without causing disturbance a method has been suggested, according to which in the first place a resistance is inserted in the primary winding of the series connected transformer the resistance being increased and the primary winding short circuited just prior to its disconnection from the supply. This allows the secondary winding of the transformer lying in series with the network to be then directly bridged over and thereupon to be completely separated from the net work. For this purpose step switches may suitably be used, which have a contact track or are constructed in the manner of change-over switches. For operating the arrangement the same care must be observed as when using high tension apparatus, and the use of automatically acting devices is therefore difficult and expensive.

A more simple and suitable solution of the problem is obtained by using a device which enables the preparatory switching operations to be effected in a low tension circuit, so that the switches lying in the high tension circuit can be of normal construction and be operated in a normal manner. The object of the present invention is to provide an arrangement for disconnecting and removing series connected transformers from the circuit, in which on the series transformer core, besides the primary winding and the secondary winding which is in series with the net-work, there is a tertiary winding which is short-circuited by a resistance before the series connected transformer is disconnected, so that the disconnection of the primary winding, followed by the direct bridging over of the secondary winding and before the disconnection and complete removal of the series connected transformer from the circuit can be effected.

In the accompanying drawing a diagrammatic representation of the arrangement according to the invention is shown.

In this drawing 1 is the primary winding, 2 the secondary winding of the series connected transformer, 3 a tertiary winding 50 which is on the iron core of the series con-

nected transformer and can be short-circuited through the resistance 4 by means of the switch 5. 6 is the bridging switch for the secondary winding 2 which may be completely cut out of the circuit by means of the knife switches 7 and 8. 9 is the switch for disconnecting the primary winding from the network. The switch 9 and the knife switches 7 and 8 are closed when under load, while the switches 5 and 6 are open.

The series connected transformer is disconnected and removed in the following manner:

First of all the switch 5 is closed and then the switch 9 is opened. Thereupon the bridging switch 6 is closed and the knife switches 7 and 8 are opened. This disconnects the series connected transformer and entirely separates it from the network. The advantage of this arrangement as compared with those hitherto used resides in the fact that quite normal simple switches (not change-over switches) can be used. The number of turns of the tertiary winding is made such that the voltage of the circuit of this winding is a low voltage. The switch 5 and the resistance 4 can thus be made for low voltage and are therefore cheaper than is the case in the known methods. As the winding 3 and the resistance 4 are loaded only for a very short time, they may be dimensioned accordingly. The series connected transformer will thus not be substantially larger than hitherto in spite of its tertiary winding.

Whether the primary winding of the series connected transformer is connected directly to the network or whether this is effected by a separate transformer, for instance a regulating transformer, is immaterial as regards the provision and operation of the tertiary winding on the series connected transformer. In this case it is also unimportant whether the primary winding is disconnected by breaking the primary circuit of the series or of the regulating transformer.

The resistance is preferably made with one step only but in special cases a plurality of bridging resistances may be used in series or a resistance may be used which

- is adjustable or regulable in any suitable manner. The size of the resistance is made such that the short-circuit voltage transmitted after short-circuiting the circuit of the tertiary winding to the secondary winding will differ no more from the previous secondary voltage than may be regarded as permissible in view of the disturbance in the work of the network to be avoided.
- 5 When in the three winding transformers of the figure the circuit of the winding 3 is closed through the switch 5 over the resistance 4, without the switch 9 being simultaneously opened, i. e. the primary winding 1 being separated from the network, this does not constitute a short-circuit of the transformer or of the network, as the resistance 4 limits the current of the winding 3 to a value corresponding to a permissible load.
- 10 If in such a case the network feeding the winding 1 has temporarily also an additional load, this does not in any way constitute a disturbance of the network operation. If the switch 9 is opened, then the current-carrying winding 2 has an exciting action on the transformer, and in its turn generates a current in the winding 3, which current produces a flux that counteracts the flux of the winding 2. The voltage, which then prevails at the terminals of the winding 2, is a function of the resistance 4 in the circuit of the winding 3, because this resistance is a part of the impedance of this circuit and determines that voltage at the terminals of the winding 3, which is required for driving the induced current through the resistance. If the winding 2 is however bridged over by the bridging-over switch 6, then both winding 2, and the circuit of the winding 3 becomes currentless. The insertion of the bridging-over switch consequently also produces no disturbance in the network of the winding 2, because no short-circuit of a network supplying voltage is caused thereby.
- 15 The fact that then the opening of the switches 7 and 8 can take place without any disturbance, is clearly evident.
- 20 What I claim is:
1. An arrangement for disconnecting and removing a series connected transformer from a circuit including primary and secondary transformer windings, switch means connected with the primary winding, a network, switch means for connecting the secondary winding in series with the network, a bridging switch in the network for short circuiting the secondary winding, a tertiary winding and resistance, and switch means to short circuit the tertiary winding through the resistance.
2. An arrangement as claimed in claim 1, characterized by the feature that the number of turns of the tertiary winding is made such that the voltage of the circuit of this winding is a low voltage.
- 25 3. An arrangement as claimed in claim 1, characterized by the feature that the tertiary winding and the resistance connected up in its circuit carry a comparatively large current as soon as the primary circuit is open are loaded with high current density.
4. An arrangement as claimed in claim 1, characterized by the feature that the size of the resistance connected up in the circuit of the tertiary winding is made such that the induced voltage in the secondary winding due to the current that flows in the tertiary winding circuit after the tertiary winding circuit is closed will differ no more from the previous secondary voltage than may be regarded as permissible in view of the disturbance in the work of the network to be avoided.
5. A method of removing a series connected transformer having a tertiary winding in addition to the usual primary and secondary windings from operation in a network, which consists in first loading the tertiary winding with a resistance, breaking the circuit of the primary winding, short circuiting the secondary winding and finally opening the secondary circuit between the short circuiting points.
- 100 In testimony whereof I have signed my name to this specification.
